UNITED STATES PATENT OFFICE.

SVEN MALKE, OF MILWAUKEE, WISCONSIN.

VALVE ATTACHING AND INFLATING MACHINE.

Application filed June 30, 1926. Serial No. 119,781.

This invention relates to a valve attaching and inflating machine for the inner tubes of tires.

Heretofore, it has been the universal practice to manually insert and lock the filling nipples or valves to the inner tubes and to thereafter inflate the tubes. This procedure has necessarily been slow and laborious and has, therefore, consumed quite a material amount of time.

This invention is designed to overcome the defects noted above and objects of such invention are to provide a machine for attaching and locking the nipple or valve in place and for automatically inflating the tubes, so that the operator may rapidly position the tubes upon the machine, such tubes being automatically discharged from the machine with the valve attached and with the tube in inflated condition.

Further objects are to provide a novel machine adapted to perform the operations heretofore manually performed, and to yet provide a machine which is of very simple and practical construction, and one which is thoroughly reliable in operation.

Further objects are to provide a machine for attaching the valves to inner tubes with subsequent inflation of such tubes and to so construct the mechanism that the valve receiving chucks or units are rocked into a position to adapt them for the ready reception of a valve, and the ready positioning of a tube, and to thereafter rock the chucks downwardly into the position where they may be inflated.

An embodiment of the invention is shown in the accompanying drawings in which:—

Figure 1 is a vertical sectional view through the apparatus;

Figure 2 is a fragmentary plan view thereof;

Figure 3 is an enlarged sectional view on the line 3—3 of Figure 2;

Figure 4 is a sectional view on the line 4—4 of Figure 3;

Figure 5 is a sectional view on the line 5—5 of Figure 3.

Referring to the drawings, it will be seen that the machine comprises a horizontal

frame work 1 supported by a plurality of spaced vertical standards 2, and joined thereto by means of diagonal braces 3. These members are all preferably of tubular construction. The inner ends of the horizontal members are received by a central bearing 4 through which a vertical hollow spindle 5 projects. This spindle carries a bevel gear 6 adjacent its lower end and is received in a suitable bearing 7. The spindle is supplied with compressed air by means of the supply pipe 8, for a purpose hereinafter to appear. Further, it is to be noted that the bevel gear is driven by a bevel pinion 9 carried by a driving shaft 10, driven from any suitable source of power.

The outer ends of the horizontal radial arms 1 are joined by means of an annular track 11 having upper and lower flanges, as shown most clearly in Figure 1.

The spindle 5 carries a central hollow head 12 which may be equipped with a gauge 13, if desired, and which receives the inner ends of a plurality of radial arms 14. The outer ends of the arms are joined by means of an annular member 15, preferably of channel shape to secure the maximum strength and lightness. All of the arms are closed at their outer ends to prevent escape of air, and certain of the arms are provided with downwardly extending air pipes 16 which communicate with an annular air pipe 17. This annular air pipe supplies a plurality of radial outwardly projecting pipes 18, as may be seen from Figures 1 and 2. These pipes are each provided with a cut off manually operable valve 19, and with an automatic valve 20, the valve 20 being provided with a crank arm equipped with a cam operated roller 21, hereinafter described in greater detail.

The annular channel shaped member 15 carries a plurality of downwardly and outwardly extending diagonal arms 22 arranged at regular intervals. These diagonally extending arms 22 carry short, horizontal, hollow shafts 23, which are connected at one end with the air supply pipe 18. (See Figure 3.) These hollow shafts 100

also pivotally carry the heads 24 of chucks, such heads being provided with projecting arms 25 which carry controlling or guiding rollers 26, fitting within the track or channel 11, and thus control the position of the chucks. The major portion of the track 11 extends in a horizontal plane completely around the machine, but it is to be noted from Figure 2 that a portion of the track 10 is deflected outwardly and downwardly, as indicated at 27, and is joined by a horizontal portion 28. Thus, the rollers 26 are held in the position shown in Figure 3 throughout the major portion of travel, but 15 when they strike the portion 27 at the lower side of Figure 2, they are deflected downwardly and outwardly into the portion of the track, indicated at 28, thus rocking the chucks upwardly. Thus camming means 20 are provided for holding the chucks in upper position to permit the ready insertion of the valve end into an inner tube, as will hereinafter appear. As they pass from the portion 28 to the other deflected part 27 25 they are rocked back into their normal position.

The chucks each comprise a central hollow stem 29 upon which is revolvably mounted a sleeve 30. This sleeve is rigidly locked to a 30 manipulating lever 31, as shown in Figure 3. Further, the sleeve 30 is provided with an inwardly projecting bottom flange 32. This flange 32, as may be seen from Figure 4, is provided with an oval or rectangular 35 shaped opening 33 through which the stem 34 of the tire valve or nipple may project, when inserted therein. However, two of the sides of the opening 33 are provided with internal threads 35, which normally engage 40 the threaded part of the valve stem 34, when the valve is locked to the chuck. However, to permit inserting the valve, the lever 31 is given a quarter swing to bring the teeth 35 of the flange 32 opposite the flat face 36 of 45 the valve. Thus, the valve may be readily inserted and thereafter the lever rocked a quarter of a turn to lock the valve in place and to draw the valve inwardly. The inward motion of the valve forces its outer end 50 against a gasket 37 (see Figure 3) mounted within the central portion 29, of the chuck, this gasket being carried by an inwardly extending shoulder. It is to be noted also 55 from Figure 3, that the central stem 29, carries within its interior a downwardly projecting rod 38 which is adapted to displace the valve stem of the valve proper so as to permit the ready entrance of the pressure air.

60 The sleeve 30 revolvably carries the hub 39 of a pulley 40. This hub is threaded at its lower end and carries a shell like sleeve 41 which extends downwardly around the valve 34, and is provided with a recessed lower 65 portion adapted to receive the nut 42 of the

valve stem. In the normal operation of the machine, the valves are received by the machine with the nut unscrewed, as illustrated in Figure 3, and with the washer or bearing member 43 positioned between the 70 head of the stem and the nut 42. It is to be noted from Figure 3 that the lower end of the extension or shell 41 of the pulley hub is socketed and is adapted to rest upon the nut 42, when the parts are in the position 75 shown in Figure 3. Further, it is to be noted that the pulley is supported by the nut and, consequently, the nut is held in the socket of the sleeve 41.

When there is no valve stem held in the 80 chuck, the bottom of the hub is adapted to rest upon the flange 44 of the sleeve 30 to prevent the pulley from sliding from the sleeve.

It is to be noted from reference to Figure 85 2 that a pin 45, as indicated in the lower portion of the figure, is carried by the stationary frame and is adapted to engage the lever 31, when the rotary member travels in the direction indicated by the arrow, thus 90 rocking the lever into chuck unlocking position and permitting the valve stem and the tube carried thereby, to drop from the chuck. It is to be noted further from reference to Figure 2 that a cam 46 is provided 95 for rocking the levers of the valve 20 into valve closing position, such cam member 46 engaging the rollers 21 of the valve. Further, it is to be noted from same figure, that a second cam 47 is provided for rocking 100 rollers 21 into valve opening position to permit the entrance of air through the chuck and to the tube.

Means are provided for rapidly rotating the pulleys 40 while the rotary member is in 105 motion. This means comprises an endless belt 48 (see Figure 2) which travels on pulleys 49, and which engages the pulleys 40 as they pass the inner stretch of the belt. Thus the pulleys 40 are rapidly rotated and screw 110 the nuts 42 (see Figure 3) of the valves into locking position.

The operation of the machine is as follows: The operator drops a valve into an upturned chuck, as shown at "A" in Figures 115 1 and 2. He then rocks the lever 31 into the dotted position shown in the lower left hand portion of Figure 2, thus causing the teeth or threaded portions 35 of the flange 32 (see Figures 3 and 4) to engage the 120 threaded portion of the valve and to thus lock the valve in place. He then fits the apertured portion of the inner tube 50 over the inner head of the upturned or inverted valve, as shown in dotted lines on the right 125 hand side of Figure 1. It is to be understood that the revolving member is continuously in motion and that these operations may be quickly performed by the attendant. As the machine rotates, the chucks are moved 130

back into their downwardly extending position as they pass the inwardly directed portion 27 of the track 15. In addition to this, the air is turned on and the inflation of the inner tube begins. As the machine rotates, the pulleys 40 are engaged by the rapidly traveling belt 48 and the nut 42 is quickly screwed down into locking position, thus locking the valves to the inner tubes. As the machine continues to rotate, the inflation of the tires continues until they are brought to the desired pressure, as indicated by the gauge 13. By this time, the machine has almost completed a revolution and the lever 31, as shown in the bottom portion of Figure 2 is about to strike the pin 45. Continued motion of the machine causes the lever 31 to be rocked into detaching position, thus permitting the inflated tube with its attached valve to drop from the machine. Just prior to this operation, the air is cut off by the action of the cam 46 on the roller 21.

It is to be noted particularly that the operator is merely called upon to drop a valve into an upturned chuck to lock the valve in place, and to fit the apertured portion of the inner tube over the end of the valve. The machine thereafter carries the parts around in its rotation, screws the nut into place and inflates the tube, finally dropping the tube and valve from the machine.

It will be seen, therefore that an automatic machine has been provided for locking the valves in place and for inflating the tubes so that a very rapid operation may be secured. In addition to this, the effort on the part of the operator is reduced to a minimum, as he has merely to perform three simple operations, namely, the dropping of the valve into place, the rocking of the lever 31, and the fitting of the inner tube over the end of the valve. Thereafter, all the other steps are automatic even to the discharging of the tube from the machine.

It is to be noted further, that the tubes are all inflated to the same pressure and, in addition thereto, that the nuts are all screwed down against the washers 43 (see Figure 3) to the same degree of pressure.

It thus follows that an absolutely uniform product results.

It is to be noted further that the machine is of very simple and of eminently practical construction.

Further, it will be seen that the machine comprises a relatively small number of parts, easily produced and assembled by ordinary machine shop processes, without requiring elaborate castings or difficult operations.

Further, it is to be noted that the machine may be operated even by an unskilled laborer with assurance that the product will be of uniform quality.

Although the invention has been described in considerable detail, such description is

intended as illustrative rather than limiting as the invention may be variously embodied and as the scope of such invention is to be determined as claimed.

I claim:

1. A machine for attaching valves, provided with shanks and locking nuts to inner tubes, said machine comprising a carrier, a plurality of chucks carried by said carrier and adapted to receive said valves, each of said chucks having a revolubly mounted member for engaging the nuts and having a gripping member for engaging said shanks of said valves, means for rotating said revolubly mounted member, and means for releasing said gripping means after said nuts have been screwed down. 70

2. A machine for attaching valves to inner tubes and for inflating such tubes, comprising a movable carrier having a plurality of valve receiving chucks thereon adapted to receive a valve with the nut backed away from the end of the valve, means for turning the chucks upwardly to permit positioning of the valves and positioning of the tube upon the valve, means for rocking the chucks downwardly and screwing the nut into locking position, and means for inflating the tire while the tire and valve are supported from the chucks. 85

3. A machine for attaching valves to inner tubes, comprising a movable member having a plurality of valve receiving chucks thereon adapted to receive and hold the valves with the inner tubes positioned on the valves, means carried by the chucks for engaging the locking nut of the valves and for screwing such nut into locking position, means for inflating the tubes while the member is in motion, and means for cutting off the supply of air after inflation, and for disengaging the chucks from the valves, whereby a plurality of tubes and valves may be acted upon by the machine at a single time. 95

4. A machine for operating upon inner tubes and valves therefor, comprising a rotary member having a plurality of chucks carried thereby, said chucks being pivotally mounted upon said rotary member and adapted to be rocked into either an upper or a lower position, said chucks being adapted for the reception of the valves, means for holding the chucks in upper position to permit the ready insertion of the valve end into an inner tube, means for subsequently rocking the chucks into lower position, means for automatically locking the valves to the inner tubes, and means for supplying compressed air to the inner tubes. 110

5. A machine for attaching valves to inner tubes, comprising a rotary member having chucks positioned at regular intervals thereon, said chucks having valve receiving portions adapted to receive filling valves with the locking nuts partially unscrewed, 125

cam means for holding the chucks in upper position to permit the ready insertion of the valves into the tube and for subsequently rocking the chucks into lower position, 5 means for rotating a portion of the chucks for screwing the nuts into locking position, means for admitting compressed air to said tubes, and means for cutting off the air sup-

ply and discharging the valves and tubes from the machine.

In testimony that I claim the foregoing I have hereunto set my hand at Milwaukee, in the county of Milwaukee and State of Wisconsin.

SVEN MALKE.
